DESIGN FOR A REFRIGERATOR CABINET

Clarence Wexelberg, Detroit, Mich., assignor, by mesne assignments, to General Household Utilities Company, Chicago, Ill., a corporation of Delaware

Original No. 93,314, dated September 11, 1924, Serial No. 46,312, December 5, 1932, for 14 years. Application for reissue February 15, 1935, Serial No. 55,455. Term of patent 14
years

To all whom it may concern:

Be it known that I, Clarence Wexelberg, a citizen of the United States, residing in Detroit,
in the county of Wayne and State of Michigan,
have invented a new, original, and ornamental Design for Refrigerator Cabinets, of which the following is a specification, reference being had thereto to the accompanying drawing, forming a part thereof, in which:

Fig. 1 is a front elevational view of the refrigerator cabinet showing my new design.

Fig. 2 is a front perspective view thereof.

I claim:

The ornamental design for a refrigerator cabinet substantially as shown.
